UNITED STATES PATENT OFFICE.

CLAUDE A. P. TURNER, OF MINNEAPOLIS, MINNESOTA, ASSIGNOR TO T. WEGENER, OF COLUMBUS, OHIO.

CENTERING OR FORM FOR REINFORCED CONCRETE STRUCTURES.

Application filed June 1, 1920. Serial No. 385,571.

To all whom it may concern:

Be it known that I, CLAUDE A. P. TURNER, a citizen of the United States, residing at Minneapolis, in the county of Hennepin and 5 State of Minnesota, have invented certain new and useful Improvements in Centering or Forms for Reinforced Concrete Structures, of which the following is a specification, reference being had therein to the accompanying drawing.

The main object of my invention is to provide an inexpensive, easily handled metal-type centering for the slab, column and beam (when beams are used) members of reinforced concrete structures and one which will assure rapid removal or elimination of excess water in the concrete, and with the known benefit of quick elimination of water on the consolidation and strength of the 20 concrete. My invention therefore, consists in the centering having the characteristics substantially as hereinafter set forth and defined by or included within the scope of the appended claims.

I illustrate, and shall describe my invention as embodied in centering for beam and slab construction, but without intending to restrict my invention thereby beyond the 25 scope of my claims.

In the drawings:

Fig. 1 is a top plan view of such centering, parts being broken away to better illustrate the construction;

Fig. 2 is a vertical section on the line 2—2 35 of Fig. 1;

Fig. 3 is a vertical section on line 3—3 of Fig. 2;

Fig. 4 is a detail plan view showing the joist construction.

Described in a general way, my invention, in the case shown in the drawings, comprises post or uprights, joists attached thereto, floor supporting stringers on the joists, all of these members being made of channels 40 and detachably and adjustably connected together, and each member made of sections or units detachably and adjustably assembled; a composite flooring made of sheet metal members, one of corrugated iron or 45 steel that rests on the stringers and the other of flat or plane sheets of iron or steel that rest on the corrugated members, each of said members being composed of sections or units that are alike for each member, and are detachably and adjustably united or joined;

horizontal troughs that constitute the beam forms, and made of sheet metal parts that are detachably and adjustably connected or assembled; and column forms with side walls of sheet metal parts 60 and detachably and adjustably connected or assembled. By reason of the detachable and adjustable characteristics of the various members or elements of the organization, the same centering can be repeatedly used for 65 different jobs, and for jobs whose dimensions vary vertically and two ways horizontally.

All the form members with which the concrete has contact are provided with numerous holes or perforations through 70 which excess water in the concrete passes and is thereby quickly eliminated, thus facilitating the rapid consolidation of the concrete and assuring the desired density and strength thereof. Tests have shown that the 75 presence or absence of these drainage holes means a difference in the strength of the set concrete of from one-third to one-half.

Proceeding now with a description in detail, of what is shown in the drawings, the 80 posts or uprights 10 consist of sections or units of angles that lap past one another and are detachably and adjustably joined, as by means of headed pins 11 that pass through registering holes 12 in the overlapping webs, these pins being secured by a key or cotter 13, so that they can easily and quickly be secured or released. At the bottom, the posts rest on double wedges 14 which afford an efficient and quickly applied and removed means for such close vertical adjustment of the post as may be necessary.

At the upper ends of the posts that are in the same straight line, are detachably secured, by the headed pin and cotter device 15, the joists 16, formed each of channel sections or units that are lapped and detachably and adjustably connected as by the headed pin and cotter device, and upon the 100 joists 16 are laid the stringers 17, also of channel sections or units, detachably and adjustably connected.

Laid upon the stringers are oblong, corrugated thin gage sheets 18 of standard size, 105 that lap at sides and ends so that they form a support coextensive with each panel area, for the flat floor oblong sheets 19 of thin gage metal that are laid thereon, overlapping at sides and ends to form a smooth, 110

flat, continuous expanse to receive and support the concrete for the floor or roof slab, the overlapping portions being united to prevent displacement by the simple expedient of dropping short wire nails 19' through alining holes 20, the sheet being provided throughout its extent, with such holes for the drainage of water. Similar holes 21 for the same purpose are provided in the cornered sheets to drain the latter. The cornered sheets by reason of their corrugations, furnish a strong and rigid support for the floor plates, and thus the composite floor member has the admirable qualities of stiffness, or rigidity, and strength, smoothness or flatness, and lightness, as well as ability to eliminate excess water in an efficient and altogether satisfactory way without loss of cement. Where the cornered sheets lap endwise, they too may be fastened together by nails dropped through alining holes 21. Where they lap at the sides, the corrugations of one interlock with those of the other and thus form an adequate union of them.

The beam forms are composed of two similar side walls 22, each with an outturned flange 23 at the top to lap the adjacent floor plates 24 and U-shaped bottom section 25 whose vertical side walls overlap and are detachably connected with the side walls 22 as by stove bolts 26, the overlap being sufficient to adequately vary the height of the beam. Said side and bottom walls are made of sections or units, lengthwise, to change the length of the beam form to suit the panel span. To make beams of varying width, a collection of U-shaped sections of assorted widths is provided. The side and bottom walls of the beam form have drainage holes 27.

To adequately support the bottom and sides of the beam form, I join in pairs posts 10 that are on opposite sides of the form and engage such sides by a horizontal section or unit 28 of channel iron, the latter and the posts being adjustably and detachably connected as by the headed pin and cotter device 29 and alining holes in the parts, and so that said unit 28 bears against the bottom of the form.

The column form consists of four similar vertical walls of sheet metal, each wall

30 being L-shaped in cross section, the four being grouped so that the flange, or angle 55 of one overlaps that of another, and the extent of overlap being determined by the diameter of the column to be cast. The four walls are supported externally, as by encircling straps, placed at proper intervals 60 vertically, each strap being composed of two like L's formed each of angle bars 31 that are joined as by a hinge pin 32 at the corner, and the bars of one L being lapped across the bars of the other and joined detachably and adjustably by the headed pin 65 and cotter device 33, and selected alining holes of a series of holes 34 formed in each bar.

The column form side walls are cut away 70 to provide a hole 35 at the top which registers with the beam form so that the concrete can join beam and column, and column form sides and beam form sides are detachably connected where they adjoin as by the 75 double angle plate 36.

The drainage holes in all the centering parts with which the wet concrete has contact, are of such size and so uniformly distributed, and are at such intervals apart as 80 generally throughout the entire centering to effect the rapid and uniform elimination of the excess water.

I claim:—

1. Centering for concrete comprising a 85 floor having an under corrugated member and an upper flat plate member resting on the corrugations of the under member, such upper member being provided with water drainage holes.

2. Centering for concrete comprising a floor having an under corrugated member and an upper flat plate member resting on the corrugations of the under member, each of such members being composed of separable units of sheet metal, and a supporting system for said floor member, comprising posts and connected horizontal members composed of adjustable and detachable units formed of overlapping structural shapes, 95 the adjustable and detachable connection being a headed pin and cotter device and holes in the overlapping portions of such shapes. 100

In testimony whereof I hereunto affix my signature.

CLAUDE A. P. TURNER.
